UNITED STATES PATENT OFFICE.

JAMES H. ROWLEY, OF CHICAGO, ILLINOIS, ASSIGNOR TO THE SYKES COMPANY, OF CHICAGO, ILLINOIS, A CORPORATION OF ILLINOIS.

DOOR STRUCTURE.

Application filed June 15, 1925. Serial No. 37,227.

The main object of the invention resides in the provision of a metal door structure of the sealed or weather proofed type which is simple and effective and well adapted for 5 its purpose with a view toward withstanding long periods of hard usage without loss of effectiveness.

With this object in view my invention consists in certain features of novelty in the 10 construction, combination, and arrangement of parts by which the said objects and certain other objects hereinafter appearing, are effected, all as fully described with reference to the accompanying drawings and more 15 particularly pointed out in the claims.

In the said drawings—

Figure 1 is a face elevation of a wall in which is installed a door structure embodying my invention.

20 Figure 2 is an enlarged partial section on the line 2—2 of Fig. 1.

Figure 3 is an enlarged partial section on the line 3—3 of Fig. 1.

25 Figure 4 is an enlarged partial section on the line 4—4 of Fig. 1.

Figure 5 is an enlarged partial section on the line 5—5 of Fig. 1.

Like characters of reference indicate like 30 parts in the several views.

Referring to the drawings 1 designates a masonry wall into a suitable opening of 35 which is secured a door frame 2. A door 3 is hinged, by means of hinges 4, at one side of the door frame for opening and closing movement with respect thereto, the door being provided with a suitable lock 5 whereby to releasably secure the door in closed position to the opposite or lock side of the frame.

The frame 2 is formed of suitable sheet 40 metal, such as cold drawn steel molded to shape, and is of open-sided outwardly facing channel formation. The door 3 is formed of suitable sheet metal such as cold drawn steel molded to shape, and is of box form, 45 the frame and door being provided with interiorly disposed relatively thick metal pieces 6 secured, as by welding, respectively to the body of the door and frame at the hinge sides thereof whereby the hinges 4 50 may be suitably mortised in and secured to the door and frame, the piece 6 of the door extending along the bottom of the door and secured therat for purposes of strength.

55 The door 3 when closed is disposed with in the opening of the frame 2 adjacent a

face of the frame, and the frame is provided with an intermediately disposed inwardly projecting molding 7 formed from the metal thereof and extending along the sides and top thereof in adjacent parallelism with the 60 inner face of the closed door. A sheet metal strip 8, preferably of cold drawn steel, is secured to the molding 7, as by welding, and extends therealong and projects from the molding normal to the plane of the door 65 frame in spaced relation therewith in the direction of opening movement of the door. The projecting edge portion of the strip 8 is bent at a right angle toward the frame and spaced therefrom forming a door stop shoulder, as designated at 9, against which the 70 door engages when closed. At the lock side and top of the frame the strip 8 forms, in conjunction with the door frame and molding 7 thereof, an open-sided channel 11 facing the closed door. See Figs. 2 and 4. An open-sided channel 12 is formed from the metal of the door at the hinge side thereof, see Fig. 5, and extends therealong immediately adjacent the side of the molding 7 adjacent the door and faces the lock side of the door frame.

The threshold is formed of relatively thick sheet metal, such as cold drawn steel, and is constructed as follows. See Fig. 3. One sheet metal member 13 thereof is of right angle section the main leg 14 of which is horizontally disposed on the inside of the door 3 and elevated above the bottom of the door, and the other leg 15 of which is disposed 80 at the side thereof farthest from the door and extends downwardly for engagement with a shoulder of the part of the masonry wall 1 forming the sill of the door opening therein and extending below a floor 16 on 85 the inside of the wall. The edge of the member 13 adjacent the door 3 extends along the face of the door when the door is closed, and a second sheet metal member 17 of right angle Z section has one of the feet 18 thereof secured by rivets 19 against the under or inside face of the horizontal leg portion 14 of the member 13 inwardly of and in 90 parallelism with the aforementioned edge of the member 13 adjacent the door. The other foot 21 of the member 17 extends outwardly from said edge of the member 13 immediately underneath the door and slants outwardly and away or downwardly from the plane of the horizontal leg 14 of the member 13 for 95 100 105 110

- purposes of drainage, this portion being on the exterior where the assembly is installed in an exterior wall. A metal strip 22 is secured, as by welding, in the angle of the 5 foot 21 of the member 17 and has its outer surface disposed in the plane of the aforementioned edge of the member 13 whereby to form a stop shoulder against which the inner face of the door engages when the door 10 is closed. By reason of the arrangement of the members 13 and 17 an open-sided channel 23 is formed on the threshold at the stop shoulder thereof and extending therealong and facing the closed door.
- 15 Thus is formed an open-sided channel on the door frame and threshold extending around the margins of the closed door and facing the inner face or plane of the closed door at the lock side, top and bottom of the 20 door and facing the lock side of the frame at the hinge side thereof.

As hereinbefore described the door 3 is formed of sheet metal and is of box form, and a marginal flange 24 is formed on the 25 door at the inner face thereof by portions of the metal of the door being bent on themselves in overlying relation. See Figs. 2, 3, 4, and 5. The flange 24 projects from the said inner face of the door normal to the 30 plane of the door at the top, bottom, and lock side thereof and projects in the plane of the door at the hinge side thereof. When the door is closed the flange 24 projects into the channels 11, 12, and 23 and engages a 35 packing 25 of suitable material, such as felt, secured in said channels and extending therealong, thereby effectively sealing or weather proofing the door opening, the arrangement of the channels and flange as hereinbefore 40 described permitting opening and closing of the door.

It will be observed that a simple and rugged construction is provided which is well adapted for long usage, and that the packing 45 in the channels is protected against accidental damage or displacement. Furthermore the packing is not exposed and is not liable to be affected by weather conditions.

While I have herein shown and particularly described the preferred embodiment of my invention I do not wish to be limited to the precise details of construction shown as changes may readily be made without departing from the spirit of my invention, but 50 having thus described my invention I claim as new and desire to secure by Letters Patent 55 the following:—

1. The combination in a sheet metal door frame and hinged sheet metal door assembly, 55 of a marginal flange on the door and formed from the metal thereof and extending along the sides and top at the inner face thereof and projecting in the direction of closing movement of the door at the top and lock side thereof and in the plane of the door at

the hinge side thereof, an intermediately disposed inwardly projecting molding on the door frame and formed from the metal thereof and extending along the sides and top thereof, a metal strip secured on said molding and extending therealong and projecting therefrom normal to the plane of the door frame opening in spaced relation with the frame in the direction of the door and forming a stop therefor and an open sided channel facing the closed door at the top and lock sides of the frame, and an open sided channel formed from the metal of the frame at the hinge side thereof and extending therealong immediately adjacent the side of the molding adjacent the door and facing the lock side of the frame, said flange being adapted to project into said channels when the door is closed for engagement with packing secured therein.

2. The combination in a sheet metal door frame, threshold and sheet metal door assembly, of a marginal flange on the door and formed from the metal thereof and extending along the top, bottom, and sides at the inner face thereof and projecting in the direction of closing movement of the door at the top, bottom and lock side thereof and in the plane of the door at the hinge side thereof, an intermediately disposed inwardly projecting molding on the door frame formed from the metal thereof and extending along the sides and top thereof, a metal strip secured on said molding and extending therealong and projecting therefrom normal to the plane of the door frame opening in spaced relation with the frame in the direction of the door and forming a stop therefor and an open-sided channel facing the closed door at the top and lock sides of the frame, an open-sided channel formed from the metal of the frame at the hinge side thereof and extending along said side immediately adjacent the side of the molding adjacent the door and facing the lock side of the frame, a shoulder extending along the threshold and facing the closed door and forming a stop therefor, and an open-sided channel at said shoulder and extending therealong and facing the closed door, said flange being adapted to project into said channels when the door is closed for engagement with packing secured therein.

3. In a metal threshold the combination of a sheet metal member, a second sheet metal member of right angle Z section having one of the feet thereof secured against a face of the first-mentioned member inwardly of and in parallelism with an edge of said first mentioned member and having the other foot thereof extending in a direction outwardly of said edge, and a metal strip secured in the angle of the other foot of said second member as and for the purpose described.

4. In a metal threshold the combination of a sheet metal member of right angle section, a second sheet metal member of right angle Z section having one of the feet thereof secured against the inside face of the first mentioned member inwardly of and in parallelism with an edge of said first mentioned member extending along the angle thereof and having the other foot thereof extending outwardly from said edge and slanted outwardly and away from the plane of that portion of said first mentioned member to which said second member is secured, and a metal strip secured in the angle of said second mentioned foot of said second member and having its outer surface disposed in the plane of said edge of said first mentioned member.

5. The combination with a sheet metal door frame of an intermediately disposed inwardly projecting molding thereon and formed from the metal thereof and extend-

ing along the sides and top thereof, a sheet metal strip secured on said molding and extending therealong and projecting therefrom normal to the plane of the door frame opening in spaced relation with the frame in the direction of opening movement of a door, hinged to the frame, and having the projecting edge portion thereof bent at a right angle toward the frame and spaced therefrom and forming a door stop shoulder and an open-sided channel facing the closed door at the top and lock side thereof, and an open-sided channel formed from the metal of the frame at the hinge side thereof and extending along said side immediately adjacent the side of the molding adjacent the door and facing the lock side of the frame, as and for the purpose described.

In witness whereof I hereunto affix my signature this 8th day of June, 1925.

JAMES H. ROWLEY.
